US0D1009979S

(12) **United States Design Patent** (10) **Patent No.:** **US D1,009,979 S**
(45) **Date of Patent:** **** Jan. 2, 2024**

(54) **BRIDGE FOR GLASSES**

(71) Applicant: **Eyenovation.DC LTD.**, Petach Tikva (IL)

(72) Inventor: **Dror David**, Petach Tikva (IL)

(73) Assignee: **Eyenovation.DC LTD.**, Petach Tikva (IL)

(**) Term: **15 Years**

(21) Appl. No.: **29/739,106**

(22) Filed: **Jun. 23, 2020**

(51) LOC (14) Cl. **16-06**

(52) U.S. Cl.

USPC **D16/332**

Primary Examiner — Sanjeev Paul

(57) **CLAIM**

The ornamental design for a bridge for glasses, as shown and described.

DESCRIPTION

FIG. 1 is a front perspective view of a bridge for glasses showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate environmental structure that forms no part of the claimed design.

1 Claim, 5 Drawing Sheets
